UNITED STATES PATENT OFFICE

2,500,343

STOP MECHANISM FOR FLY FRAMES

Maurice Carrette, Lille, France, assignor of one-half to Societe Le Blan & Cie, Lille, France, a French company

Application November 4, 1946, Serial No. 707,680
In France April 23, 1946

6 Claims. (Cl. 57—78)

1

When a sliver or strand is broken during the operation of a fly frame, it generally becomes entangled in the adjoining slivers, causes other snappings and in the majority of cases leads to important trouble in the running of the machine.

It is well known that those slivers are fragile, that their consistence is very weak and that it is not possible to apply pressure to them without causing them to break up. That is why the majority of known knocking off devices using feelers which come into contact with the sliver could not be applied to fly frames.

It is however highly desirable to be able to halt the frame as rapidly as possible after a sliver has snapped; that is why the workers controlling those machines have to lose a great deal of their time supervising the running and to be ready to intervene at once should a sliver snap.

Furthermore, as fly frames generally work with double slivers, that is to say two slivers rolled at the same time so as to combine to form only one, it sometimes happens that only one sliver is being worked and the final result or "single" is thus defective.

It so happens that the staff often fail to observe the incident or hits upon it only a rather long time after the occurrence. The operators are then obliged to lose a good deal of time in remedying the failures produced by the machine.

It has already been proposed to cause the sliver to pass before the suction inlet of a fan in such a way that when a sliver snaps, the material of which it is composed is at once drawn in the fan and is thus unable to get entangled with the neighbouring slivers. Should a single occur, it is likewise drawn into the suction inlet after a very short while.

The object of the present invention is a stopping mechanism for fly frames comprising, in combination, a suction device of the type mentioned above and means for automatically stopping the fly frame without any interference by the staff, as soon as a sliver snaps or if a single is produced.

The improved stopping mechanism comprises also a signalling device giving warning of the stoppage of the machine. By being warned in such a manner, someone of the staff can at once see to the snapping or to the single and then set the machine running again. The workers in charge no longer need to have any fear of breakage or of defects that have not been perceived very rapidly; and their time and attention may be reserved entirely for productive work.

2

Other features of the invention will appear from the following description.

In the accompanying drawings:

Fig. 1 is an elevation view, with parts broken away, of a stopping mechanism in accordance with the invention;

Fig. 1^a is a partial plan view of the device corresponding to the position shown in Fig. 1.

Fig. 2 is a partial view of the device when the frame has been stopped;

Fig. 3 shows a modification;

Figs. 4, 5 and 6 show another modification in three successive stages of operation.

Figs. 7 and 8 show further embodiments of the invention.

As shown in Figs. 1 and 2, the slivers or strands 1 delivered by the cylinders 2 are wound upon the bobbins 3 after passing in front of the inlet openings 4 of a suction pipe 5 connected to a fan 6 through a cylinder 7. A perforated piston 8 adapted to move in said cylinder carries a piston rod 9 provided with an enlarged flat part 9' and which is pivotally connected at 10 with a lever 11 oscillating around a fixed axis 12 of a mercury or other switch 13. The switch 13 is arranged in the circuit 14 of a coil 15 adapted to raise and release a bar 16 which is normally blocked by a stop member 17 and pivotally connected at 18 to a bell crank lever 19. The lever 19 is pivoted around a fixed axis 20 and is urged in the direction of the arrow f¹, for instance, by a counterweight 21, a spring or any other equivalent device.

The vertical arm of lever 19 is adapted to push to the right a shoulder 22 fixed on a release bar 23 carrying a fork 24 used to shift a power belt —not shown—from a fixed pulley 25 on to a loose pulley 26 and vice versa.

The device is completed by a lever 27 oscillating around a fixed axis 28. This lever is hinged by means of a slot on a pin 29, carried by the bar 23. Its lower end embraces the cylindrical part of the piston rod 9 with two legs 27' and 27'', a pawl 31 being hinged on an axis 30 carried by the leg 27, one end of pawl 31 forms a hook 32, intended to cooperate with a lateral projection 33 on the enlarged part 9' of the piston rod 9, while the heel of the lever cooperates with a cam member 34 fastened to the bottom of cylinder 7.

The operation is as follows: when a sliver 1 breaks, the material delivered by the cylinder 2 is at once drawn by the fan 6 and is thus unable to become entangled with the adjacent slivers. Should a single occur, after a very short

lapse of time this also is drawn into the pipe 5.

The piston 8 is interposed in the suction circuit and when the material enters that circuit it stops up the holes in the piston. Suction by the fan thus results in a difference of pressure on the opposite faces of the piston and the latter moves to the left as shown by arrow f^2 .

As the rod 9 pushes on the lever 11 it closes the electric circuit 14 by rocking the mercury switch 13 (Fig. 2). The electric circuit 14 being closed, the electro-magnet 15 is energized and it raises the bar 16 which is thus set free from the locking member 17; the bell crank lever 19 is released and under the action of weight 21 it causes the bar 23 to move to the right as shown by arrow f^1 . Said bar by means of the fork 24 causes the driving belt on the fixed pulley 25 to pass on to the loose pulley 26. The fly frame is thus caused to stop.

The closing of the electric circuit and/or the displacement of the belt will simultaneously start a signal by any desired means such as an electro-signal diagrammatically shown at S in series in the electric circuit 14. The signal may be either mechanical, a fixed or blinking light, some sound signal or even those three at the same time so as to attract the operator's attention and to indicate the stoppage of the machine. It also shows him the particular machine that has stopped when there is a group of similar machines.

In the latter part of the movement of bar 23 to the right, the piston 8 is drawn further inwardly by the lever 27 as it comes into contact with the enlarged part 9' of the piston rod 9 (see Fig. 1a and Fig. 2) and finally, it partially moves past the suction aperture 35. All the fibers accumulated on the forward face of the piston are then dragged into the aperture 35 so as to clear the piston.

When the operator has fastened the broken sliver 1 or has removed the single, he sets the machine running again; to do this, he pushes the release bar 23 to the left. The lever 27 oscillating around the fixed axis 28, will thus displace to the right the pawl 31, 32 which has then engaged the lateral projection 33 on the enlarged part of 9' of piston rod 9. The piston is thus returned to the position it occupied in Fig. 1 and is thus ready for a further operation. At the end of the return movement, the heel of pawl 31 moves along the cam 34 which rocks and is released from the projection 33. The piston will then be able to move again to the left as soon as another breakage of a sliver occurs.

In the modification shown in Fig. 3, the electro-magnet 15 mentioned above is controlled by means of an adjustable differential manometer 36 cooperating with electric contacts 37, 38 arranged in the circuit 14 of the electromagnet. The manometer is operated by the difference between the pressures exerted on the opposite faces of the piston 8, its two branches 39, 40 being in communication with the chambers 41 and 42 of the cylinder. When a sliver snaps, the difference of pressure increases and the circuit 14 is closed whereby the electromagnet 15 is caused to act as explained above.

Figs. 4 to 6 show another modification in which a perforated partition or flap 9a can swing around an axis 43 in a casing 44, the side faces of which are parallel whereas the lower surface 45 is cylindrical and coaxial with pivot 43. The casing 44 is in communication at 46 with the suction pipe 35 described above.

On the pivot 43 is secured a supporting mem-

ber 47 carrying a mercury switch 13 connected with the circuit 14 of the electromagnet.

Under the effect of the depression in the pipe 35 when a sliver snaps, the difference of pressure set up on the opposite faces of the partition causes the same to swing to an inclined position so that the switch 13 will close the circuit 14 and the driving belt will be moved from the fixed pulley to the loose pulley as described above.

10 The release bar 23 is then moved to the right by the counterweight, as shown by arrow f^1 , and the flap 9a is thus caused to rock beyond the point 46 under the action of a dog 23' fixed on the bar 23, so as to be cleared from the accumulated sliver (Fig. 6). When the operator sets the machine to work again, the flap 9a is brought to its original position.

15 In the modification shown in Fig. 7, the switch 13 which can oscillate around an axis 50, is connected by a link 51 to a two arm lever 52 which oscillates around an axis 53. At 54, that lever is connected to the bell 55 of a vacuum meter moving vertically in a tank 56 which forms a hydraulic joint. A tube 57 is used to connect the 20 inside of the bell 55 with the forward chamber 42 in cylinder 7.

When a sliver snaps, the holes in the piston 8 become clogged as described above and the pressure in the chamber 42 of the cylinder 7 is increased. The suction is decreased under the bell 55 and the lever rises. The lever 52 rocks in the direction shown by the arrow f^3 and the switch 13 closes, whereby the fly frame is caused to stop.

25 The construction shown in Fig. 8 is the same as that shown in Fig. 7 with the exception that the reciprocating piston 8 is replaced by a swinging partition or flap 9a as described above with reference to Figs. 4 to 6. The lever 47 secured on the axis 43 of the flap 9a is provided with a pin 30 48 moving in a slot 49 provided in a sleeve secured on the belt shifting bar 23.

35 The piston 8 or the flap 9a can be a perforated plate or it may be made of metallic netting, of cloth or of any other substance pervious to air.

40 Having now described my invention what I claim as new and desire to secure by Letters Patent is:

1. In a fly frame for working slivers and the like, a stop mechanism comprising suction means 45 adapted to create a fluid stream, a suction pipe connected with said suction means and provided with openings before which said slivers are adapted to pass in close relation, a perforated partition between said suction means and said suction pipe and adapted to be clogged by said slivers when broken so as to cause a variation of pressure of said stream, stopping means for the frame and controlling means for operating said stopping means under the action of said variation of pressure.

2. In a fly frame for working slivers and the like, a stop mechanism comprising suction means 50 adapted to create a fluid stream, a suction pipe connected with said suction means and provided

55 with openings before which said slivers are adapted to pass in close relation, a movable perforated partition between said suction means and said suction pipe and adapted to be clogged by said slivers when broken so as to cause a variation of pressure of said stream, controlling means operated by said variation of pressure, means operatively connected to said controlling means and adapted to cause said movable partition to be brought in a retracted position for allowing the 60 communication between said suction means and

75 communication between said suction means and

suction pipe and stopping means for the frame operated by said controlling means.

3. A stop mechanism for fly frames, as claimed in claim 2, in which said movable partition is a reciprocating piston.

4. A stop mechanism for fly frames, as claimed in claim 2, in which said movable partition is an oscillating flap.

5. A stop mechanism for fly frames, as claimed in claim 1, in which said stopping means comprise an electromagnet for actuating thereof and said controlling means comprise a differential manometer the two branches of which are respectively in communication with chambers located on the opposite faces of the partition and provided with electric contacts arranged in the circuit of said electromagnet.

6. A stop mechanism for fly frames, as claimed in claim 1, in which said stopping means comprise an electromagnet for actuating thereof and

5 in the circuit of said electromagnet.

MAURICE CARRETTE.
